Ezra Ripley & N. S. Vedder, of Troy, N. Y.

Assignors to

George W. Eddy, of Waterford, N. Y.

Letters Patent No. 608. Dated Nov. 8th, 1853.

The schedule referred to in these Letters Patent, and making part of the same.

To all whom it may concern:

Be it known that we, Ezra Ripley and N. S. Vedder, of Troy, in the county of Rensselaer, and state of New York, have invented or produced a new and original design of parlor stove, which we call the "Castle", and we do hereby declare that the following is a full, clear, and exact description of the same, reference being had to the annexed perspective drawing making a part of this specification.

The ornamental design of our parlor stove is as follows; viz.

A is the front plate ornamented with the center ornament (a) composed and arranged as shown in the annexed drawing. The upper part of the plate terminates in the ornamental tower B, and the Gothic caps C, C, D, D, are sunk panels arched at the top, and ornamented with the diamond work (b, b); at each end of the plate are the notched mouldings (c, c). The end plate E, has a center ornament (d) arranged upon the panel with diamond work (e, e) at the top and bottom. F is the bottom plate decorated with the ornamental moulding (f, f). Around the edge G, is the leg with the ornamental work (g) on the face of it.

Having thus described our new design of parlor stove, what we claim as new, and desire to secure by Letters Patent, is

The ornamental design and configuration of parlor stove plates, such as herein described, and represented in the annexed drawing.

Witnesses,

J. J. Savage. }
John Moran. }

Ezra Ripley.
N. S. Vedder.
